UNITED STATES PATENT OFFICE

ALEXANDER G. RIBBERGER, OF ZANESVILLE, OHIO, ASSIGNOR TO OHIO FERRO-ALLOYS CORPORATION, OF CANTON, OHIO, A CORPORATION OF OHIO

FURNACE ELECTRODE SUSPENSION

Application filed May 27, 1931. Serial No. 540,228.

The invention relates to electric furnaces of the arc type having one or more vertically disposed electrodes suspended within the furnace.

5 More particularly, the invention relates to arc type electric furnaces having vertical electrodes, wherein it is desirable for facilitating charging and promoting even distribution of the charge within the furnace, to omit 10 the usual top wall or roof rendering the furnace open to the atmosphere.

In such electric furnaces a transformer spaced from the rear of the furnace usually supplies current for the electrodes, and the 15 current is led from the transformer through suitable conductors such as bus bars, flexible cables, and water cooled copper tubes to electrode holders supporting the electrodes, and thence to the electrodes. It is necessary to 20 suspend the electrode holders from above the furnace in such a way as to provide for an independent raising and lowering of each of the electrodes relative to the furnace, in order to compensate for the burning off or 25 consumption of the bottom of each electrode, and to maintain a substantially equal amount of current flowing through all electrodes at all times.

Because of the intense heat rising from the 30 furnace around the electrode holders, current is usually conducted to the holders by means of water cooled copper tubes, and means must be provided for raising and lowering these tubes along with the electrode holders 35 and electrodes. Current carrying cables are usually provided to effect a flexible connection between the stationary bus bars connected to the transformer and the vertically movable copper tubes.

40 In the past the electrode holders and tubes have been suspended from sheaves rotatably mounted over the furnace upon a steel framework located at the sides of and extending over the furnace. In order to provide for 45 independent vertical adjustability of each electrode, a pair of cables, one secured to each side of the electrode holder, have been passed over sheaves rotatable about a horizontal axis perpendicular to the longitudinal axis of the furnace; the longitudinal axis

of the furnace being considered as the axis extending from front to rear of the furnace to the transformer and substantially parallel with the conductors leading from the transformer to the electrodes. Each of the 55 cables passing over the sheaves then are extended from the sheaves to suitable motor driven hoisting drums or winches.

Two supporting cables have been employed for suspending each electrode, in order to 60 maintain the electrode in a true vertical position, for the reason that the electrodes are originally relatively long and are suspended from a point below their longitudinal centers.

Accordingly, in such prior structures, there 65 are two sheaves for each electrode which must necessarily be mounted on a horizontal shaft or shafts perpendicularly disposed to the longitudinal axis of the furnace, and the shafts are journaled in bearings substantially 70 directly above the electrodes. These bearings are supported upon cross members of the framework, which cross members consequently extend directly over the hottest portion 75 of the furnace.

When two or more electrodes are suspended within the furnace, the span between the side frame members is so great that intermediate longitudinal frame members are required to support the central portions of the 80 cross members; and these intermediate longitudinal members also extend over the central portion of the furnace.

If two electrodes are employed, they are arranged upon a horizontal axis perpendicular to the longitudinal axis of the furnace, and the bearings and supporting sheaves are mounted upon a single horizontal cross frame member disposed at right angles to the longitudinal axis of the furnace. If, however, 85 three electrodes are employed in the well known triangular orientation arrangement, a second cross frame member extending over the furnace is required for supporting the bearings and sheaves for the third electrode. 90

Thus the sheaves, bearings, cables, and the supporting framework therefor in such prior structures are all located directly over the furnace and subjected to intense heat. In a 100 relatively short time the effect of this heat

causes unequal expansion of the supporting cables for each electrode, resulting in the tendency of the electrode to tilt out of vertical alinement; the bearings become dry, or if the bearings are water cooled dust accumulates therein, decreasing their life and requiring additional power to raise and lower the electrodes; and the steel framework becomes corroded and warped, resulting in numerous mechanical difficulties in properly operating a furnace, such as misalignment of the various parts.

A further difficulty is experienced, in that in order to adjust any of the electrodes in a direction parallel to the longitudinal axis of the furnace, it is necessary to longitudinally move the sheaves, bearings, and supporting frame members.

It has been attempted to water cool the sheave bearings, but this requires a water circulating system and proves costly and unsatisfactory, because, even though the bearings are water cooled, the frame members exposed to the heat cannot be satisfactorily cooled.

Unless counter-weights are provided for the electrodes, the power required to raise and lower the electrodes and their heavy holders is relatively great, and this prior type of electrode suspension requires a complicated system of cables and sheaves to operatively connect the supporting cables with counter-weights located at the sides or rear of the furnace and away from the conductors.

And finally, in such prior constructions, the supporting framework required above the furnace presents an extensive surface area which substantially restricts the direction of the upward flow of the hot gases arising from the furnace, with the result that a large part of the heat is reflected instead of being immediately carried away, thereby increasing the deleterious effect upon all parts over the furnace.

It is therefore an object of the present invention to provide a construction and arrangement for vertically adjustably suspending electrodes within a furnace, which arrangement will substantially reduce the number of operating parts located directly above the furnace.

Another object of the invention is to minimize the amount of supporting framework required directly above the furnace.

A further object of the invention is to provide means for raising and lowering each electrode, which means does not require bearings or supporting framework to be located directly over the electrode.

Another object of the invention is to provide a construction for suspending electrodes for a furnace, in which construction a system of counter-weights may be easily and economically incorporated, to reduce power consumption.

A still further object of the invention is to provide means for easily adjusting the electrodes laterally and longitudinally of the furnace without requiring displacement of overhead bearings or supporting framework.

An additional object of the invention is to provide means for automatically moving the electrode holder away from each side of the electrode when it is desired to slip the electrode downwardly relative to the holder, or to replace the electrode.

A further object is to provide for maintaining alinement of each electrode holder regardless of axial twisting of its electrode.

These and other objects are attained by the parts, methods and improvements which comprise the present invention, and which are hereinafter pointed out in detail and defined in the appended claims.

In general terms the invention includes a separable electrode holder and a separable conductor holder for each electrode, a horizontal rotatable water cooled shaft located over each electrode and substantially parallel with the conductor thereto, a sheave on the shaft directly above the electrode, means connected between the sheave and the electrode holder at each side of the electrode for suspending the electrode in a vertical position, another sheave on the shaft directly above the separable conductor holder, means connecting the conductor holder with said other sheave, means for driving the shaft, electrode counter-weight means operatively connected to the shaft, and a supporting framework spaced rearwardly of the central portion of the furnace for supporting the shafts and the driving means therefor.

A preferred embodiment of the present improvements is illustrated in the accompanying drawings, in which

Figure 1 is a plan view of an electric furnace having three vertically disposed electrodes, showing the improved apparatus for suspending the electrodes in the furnace, parts being broken away to show the conductors leading from the transformer;

Fig. 2 is a front view of the furnace and electrode suspending apparatus, showing the furnace in section;

Fig. 3 is a side view partially in section, taken substantially on line 3—3, Fig. 1;

Fig. 4 is an enlarged fragmentary sectional view as on line 4—4, Fig. 3;

Fig. 5 is an enlarged fragmentary plan sectional view as on line 5—5, Fig. 3, showing the separable electrode holder clamped around the electrode, and the separable copper tube holder;

Fig. 6 is an enlarged fragmentary front elevation of an electrode and electrode holder; and

Fig. 7 is an enlarged fragmentary plan sectional view of the supporting shaft for

the middle electrode, showing the method of water cooling the shaft.

Similar numerals refer to similar parts throughout the drawings.

5 A rectangular, open top electric furnace is indicated generally at 10 having the usual steel shell 11 and refractory lining 12. The refractory walls of the furnace form the inner melting chamber 13 in which the electrodes 10 are suspended. In the drawings three vertical electrodes 14a, 14b and 14c are shown, but it will be understood that the invention applies equally to furnaces having a different number of electrodes.

15 The side 15 of the furnace may be termed the front side, and the side 16 the rear side. The horizontal axis A—A extending from front to rear of the furnace is, for convenience, termed its longitudinal axis, and the 20 usual transformer 17 for supplying current to the electrodes is preferably located upon this axis and spaced from the rear side of the furnace.

25 The electrodes 14a, 14b and 14c are preferably positioned within the furnace chamber 13 in the well known triangular arrangement as viewed in Fig. 1. The electrode 14a is preferably located on the longitudinal axis A—A of the furnace and adjacent its front 30 side 15, and the electrodes 14b and 14c are preferably located adjacent the rear side of the furnace upon an axis parallel to the lateral axis of the furnace, the electrode 14b being located to the left of, and the electrode 35 14c to the right of the axis A—A, as viewed in Fig. 1.

Current is conducted from the transformer 17 to each of the electrodes by means of a series of conductors located in substantially 40 parallel relation to the longitudinal axis A—A of the furnace. Current is conducted from the transformer 17, through bus bars 18a, flexible cables 19a, copper tubes 20a, an electrode holder indicated generally at 21a, 45 and thence through copper contact pads 22a to electrode 14a. In like manner, current is conducted from the transformer 17 through bus bars 18b, flexible cables 19b, copper tubes 20b, electrode holder 21b, and copper pads 50 22b to electrode 14b; and through bus bars 18c, flexible cables 19c, copper tubes 20c, electrode holder 21c and copper pads 22c to electrode 14c.

55 The bus bars 18a, 18b and 18c are electrical- ly and mechanically connected to flexible cables 19a, 19b and 19c respectively, by means of conductor holders 23a, 23b and 23c respectively. These holders may be one piece, substantially semi-spherical copper castings, 60 conveniently suspended from the overhead supporting framework indicated generally at 24. Means for suspending each of the conductor holders 23a, 23b and 23c may include a rod 25 connected at its lower end to the holder by links 26, and at its upper end to

a suitable insulator 27. A rod 28 is connected at its upper end to the framework 24, and a turnbuckle 29 is connected between the lower end of the rod 28 and the insulator 27 for adjusting the length of the suspending means. 70

The cables 19a, 19b and 19c are electrically and mechanically connected to the copper tubes 20a, 20b and 20c respectively by means of conductor holders 30a, 30b and 30c respectively. These conductor holders are preferably substantially semi-spherical copper castings, and are each divided vertically into two halves, as best shown in Figs. 4 and 5, for a purpose to be hereinafter described.

80 Each of the electrode holders 21a, 21b and 21c, and each of the conductor holders 30a, 30b and 30c are identical. For the purpose of convenience, only the electrode holder 21c and the conductor holder 30c will be described in detail.

85 The holder 21c is separable, and includes the two halves or members 31 and 31' adapted to be mounted at opposite sides of the electrode 14c as best shown in Figs. 5 and 6. The member 31 is provided with a rearwardly extending angular portion 32, and the member 31' with a rearwardly extending angular portion 32'. The angular portions 32 and 32' are adapted to extend inwardly at the rear of the electrode and terminate in tube receiving 90 portions 33 and 33' respectively, for receiving the forward ends of the copper tubes 20c.

95 The conductor holder 30c includes two halves or members 34 and 34' having the tube receiving portions 35 and 35' respectively, for receiving the rearward ends of the copper tubes 20c. Preferably portion 34 of the conductor holder is alined with portion 33 of the electrode holder, and portion 34' of the conductor holder is alined with portion 33' of 100 the electrode holder, so that the conductor tubes 20c extending between the holders are normally maintained in parallel relation to the longitudinal axis A—A, as indicated in full lines in Fig. 5. Each of the conductor 105 holder members 34 and 34' is preferably provided with a hanger attaching flange 36, and each of the electrode holder members 33 and 33' is preferably provided with a hanger attaching flange 37.

110 Copper contacts pads 22c are preferably provided, one for each side of the electrode and adapted to be located between the electrode and the electrode holder halves 31 and 31'. Lugs 38 may be provided on each pad 115 22c for engaging over a flange on the electrode holder and supporting the pads.

120 Means for clamping the pads 22c between the electrode 14c and the electrode holder members 31 and 31' may include bolts 39, 125 passing through suitable lugs 40 and 41 at the front and rear respectively, of members 31 and 31'. Nuts 39' may be screwed on one end of the bolts 39.

130 Thus by tightening up on the nuts 39' the

pads 22c may be clamped against the sides of the electrode to make an electrical contact between the electrode holder and the electrode, the electrode being supported by the holder.

The outer surface of each pad 22c is preferably curved as shown at 42 in Fig. 5 to conform with the contacting curved inner surface 43 of the electrode holder, so that if the electrode becomes twisted axially at any time, the position of the electrode holder will not be disturbed.

The pads and electrode holders may be hollow, and the pads, electrode holders and copper tubes 20c may all be water cooled by means of suitable connections with a water circulating system, not shown.

The electrode suspending apparatus is preferably supported upon the overhead framework indicated generally at 24. This framework may include horizontal side members 44 located substantially above the sides of and extending to the rear of the furnace. A horizontal cross member 45 extends laterally between side members 44, and preferably overlies the furnace at or near its rear wall. A second cross member 46 extends laterally between side members 44 at points rearwardly spaced from the cross member 45. To the rear of cross member 46 and between side members 44 is preferably provided a supporting grating or floor 47.

Means for vertically adjustably suspending each electrode within the furnace preferably includes a horizontal rotatable shaft supported on the framework 24 and located in parallel relation to the longitudinal axis A—A of the furnace and in substantially parallel relation to the current conductors leading to the electrodes.

The electrodes 14a, 14b and 14c are adapted to be suspended from the horizontal shafts 50a, 50b and 50c respectively, and the forward ends of each shaft preferably overlie the corresponding electrode. The shaft 50a is journaled in bearings 51a and 52a mounted upon cross members 45 and 46 respectively; the shaft 50b is journaled in bearings 51b and 52b mounted upon cross members 45 and 46 respectively and the shaft 50c is journaled in the bearings 51c and 52c mounted upon cross members 45 and 46 respectively. Preferably the bearings 51a, 51b and 51c are self-aligning relative to the shaft.

Means for rotating each shaft preferably includes a motor 53 and gear reducer 54 supported upon the floor 47. A flexible coupling 55 is provided between each shaft and its gear reducer to compensate for any misalignment of the shaft due to sagging or warping of the framework 24.

Preferably chain sheaves 56a, 56b and 56c are keyed upon the reduced end portions of shafts 50a, 50b and 50c respectively; and sheaves 57a, 57b and 57c are likewise keyed upon shafts 50a, 50b and 50c respectively, at

points overlying the conductor holders 30a, 30b and 30c respectively. Preferably these sheaves are made separable to facilitate attachment to the respective shafts.

Sheaves 56a and 57a are equal in diameter, as are sheaves 56b and 57b and sheaves 56c and 57c. Chains 58a, 58b and 58c may be secured at one end to sheaves 56a, 56b and 56c respectively and at their other end to electrode holder hangers indicated generally at 59a, 59b and 59c respectively. Similarly chains 60a, 60b and 60c are secured at one end to sheaves 57a, 57b and 57c respectively and at their other ends to conductor holder hangers indicated generally at 61a, 61b and 61c respectively.

Thus when any of the respective shafts are rotated the corresponding electrode holders and electrodes will be raised or lowered, and the corresponding movable conductor holders together with the conductor tubes will be raised or lowered accordingly. The flexible cables 19a, 19b and 19c provide for making connection between the movable conductor holders 30a, 30b and 30c and the stationary conductor holders 23a, 23b and 23c respectively, connected to the bus bars.

The effective diameters of the sheaves on each of the shafts 50a, 50b and 50c are such that less than a full rotation of the shaft will raise or lower the corresponding electrode through the vertical distance required for satisfactory and efficient furnace operation. This prevents any movement of an electrode longitudinally of the furnace as the same is raised or lowered, such as would occur if the suspending chain were allowed to wind more than one turn around the sheave.

If it is desired to change the relative position of the electrodes laterally of the furnace, the same may be accomplished by substituting sheaves of greater or less diameter as the case may require. If it is desired to change the relative position of the electrodes longitudinally of the furnace, this may be accomplished by sliding the sheaves 56a, 56b or 56c along their respective shafts.

Thus the electrodes may be adjusted laterally or longitudinally of the furnace very economically and in a relatively short time, without displacing or adding to the supporting framework, and without changing the position of the shaft or shaft bearings.

The electrode holder hangers indicated generally at 59a, 59b and 59c are identical, as are conductor hangers indicated generally at 61a, 61b and 61c. For convenience, only electrode holder hanger 59c and conductor holder hanger 61c will be described in detail.

Electrode holder hanger 59c preferably includes a triangular equalizer member 62, pivotally secured at its upper end or apex to the lower end of chain 58c, as at 63. The base of member 62 is normally maintained in a horizontal position, and at each end thereof a

linkage indicated generally at 65, is pivotally secured as at 64. The lower ends of the linkages 65 are pivotally connected to the attaching flanges 37 on the electrode holder 21c at 5 opposite sides of the electrode 14c.

The pivots 64 are laterally spaced from the vertical axis of the electrode a greater distance than the pivotal connections between the linkage 65 and the flanges 37, so that the 10 linkages are normally maintained in a downwardly inwardly inclined position relative to the electrode. The chain 58c, together with the equalizer member 62 and linkages 65, serves to support the electrode in a vertical position, and only one supporting sheave is required above the electrode.

The member 62 is preferably constructed so that the distance between its apex at 63 and its base is relatively great, so as to aid in 20 equalizing uneven loading on the linkages to maintain the electrode in a vertical position.

Each linkage 65 preferably includes a link 66 pivotally connected to member 62 as at 64, and a suitable insulator 67 pivotally connected to the link 66. This insulator serves to insulate the current flowing through the electrode holders from the overhead framework and suspending apparatus. The lower end of the insulator 67 is connected as by a bolt 25 67d to the upper end of an adjusting member 68 adapted for adjusting the length of the linkage 65 to compensate for variations in the lengths of any of its parts.

A link 69 is slidably connected to the lower 30 end of the member 68, and is pivotally connected by means of short links 70 to the upper end of a long link or bar 71. The lower end of link 71 is pivotally connected by short links 72 to the attaching flange 37 of the electrode holder.

Thus a linkage is provided which is adjustable longitudinally, and which possesses sufficient flexibility to take care of continuous lowering of the hanger when the electrode is 45 held stationary as by engagement of its bottom with the hearth of the furnace.

The conductor holder hanger 61c is similar in construction to the electrode hanger 59c, and includes a triangular equalizing member 50 62' and linkages indicated generally at 65'.

The linkages 65' are pivotally connected to the member 62' at points laterally spaced apart a distance equal to the distance between the pivotal connections of the linkages and 55 the attaching flanges 36 upon the conductor holder 30c, so that the linkages 65' normally hang vertically.

Each of the linkages 65' includes upper links 66', insulators 67', adjusting members 68' and links 69', 70', 71', and 72'. The links 72' are pivotally connected to the attaching flanges 36 upon the conductor holder.

When a considerable portion of an electrode, as for instance the electrode 14c, becomes burned off or consumed at the bottom,

it becomes necessary to slip the electrode downwardly between the contact pads 22c. This may be accomplished by unscrewing the nuts 39', whereupon the electrode holder halves 31 and 31' will move outwardly due 70 to the inclination of the linkages 65. Since the conductor holder 30c is separable also, the electrode holder half 31, conductor half 34 and tubes 20c connected therebetween are 75 permitted to swing outwardly as a unit; and the electrode holder half 31', conductor holder half 34', and tubes 20c connected therebetween are also permitted to swing outwardly as a unit. The outward positions of the holder and linkage members are substantially shown in dot-dash lines in Figs. 5 and 6. In this position of the parts, the electrode 14c may be slipped downwardly without frictionally engaging the contact pads, or may be taken out and replaced.

For the purpose of decreasing the power required to raise the electrodes, a counter-weight system for each of the shafts 50a, 50b and 50c is preferably provided. Counter-weight sheaves 76a, 76b and 76c are fixed upon the respective shafts at points horizontally spaced from the rear side 16 of the furnace, and the sheave 76a is preferably spaced to the rear of the sheaves 76b and 76c.

Cables 77a, 77b and 77c are secured at one end to the hubs of the sheaves 76a, 76b and 76c respectively, and then pass out through and around the peripheries of the sheaves to extend from the upper portions thereof outwardly laterally of the longitudinal axis of the furnace. The cables 77a and 77b extend to the left of the sheaves 76a and 76b respectively, as viewed in Fig. 1 and pass over idler sheaves 78a and 78b respectively, which are journaled on a longitudinally extending idler shaft 79. The shaft 79 is preferably fixed in bearings 80 and 81 mounted upon cross members 45 and 46 respectively. The lower ends of cables 77a and 77b extend downwardly into a counter-weight housing 82 located at the left side of the furnace, and have secured on their lower ends, suitable counter-weights 83a and 83b respectively, movable vertically in the housing 82.

Similarly, cable 77c extends to the left of sheave 76c over an idler sheave 78c journaled upon an idler shaft 85, which is fixed in bearings 86 and 87 mounted upon cross members 45 and 46 respectively. The cable 77c extends downwardly from sheave 78c into a counter-weight housing 88 located at the right side of the furnace, and the lower end of the cable has secured thereon a suitable counter-weight 83c movable vertically within the housing 88.

The counter-weight sheaves 76a, 76b and 76c are preferably of large diameter relative to sheaves 56a, 56b and 56c, from which the electrodes are suspended, so that the larger lever arm of the counter-weight sheaves en-

ables the use of counter-weights of relatively small mass to balance the respective electrodes. Since each counter-weight sheave is fixed upon the same shaft as the sheave suspending the corresponding electrode, each counter-weight sheave will rotate through less than a full rotation during the required vertical travel of the electrode.

Preferably, the shafts 50a, 50b and 50c are 10 water cooled, and are provided with inlet connection 89a, 89b and 89c respectively, and with outlet connections 90a, 90b and 90c respectively. The method of cooling the shaft 50a is illustrated in Fig. 7.

15 The shaft 50a is provided with a longitudinal bore 91 extending from its forward end to a point spaced to the rear of the bearing 51a. Water enters the inlet connection 89a and passes through a pipe 92 located axially 20 of the shaft and of less outside diameter than the diameter bore 91. Water flows through the pipe 92, to the forward end of the shaft 50a, and at the forward end portion of the shaft the pipe is provided with a series of 25 perforations 93 through which the water is sprayed upon the inner surface of the bore, thereby cooling the hottest part of the shaft. The water circulates rearwardly around the outside of the pipe 92 and discharges through 30 the outlet connection 90a.

A plug 94 is preferably screwed in the end of the bore 91, and is provided with a pin 95 entering the end of the pipe 92 for the purpose of centering the same.

35 The shafts 50b and 50c are water cooled in a similar manner.

Each of the inlet and outlet connections to the shafts may be flexibly connected to a suitable water circulation system, not shown.

40 In the operation of the furnace, assuming a current to be flowing from the transformer through the several conductors to the electrodes, if it is required to raise one electrode, as for instance electrode 14a, to adjust the 45 arcing distance between the bottom thereof and the charge in the furnace in order to adjust the amount of current flowing through the electrode, the procedure is as follows:

The motor 53 operatively connected to the 50 shaft 50a is operated to rotate the shaft counter-clockwise as viewed in Fig. 2. Rotation of the shaft 50a rotates sheaves 56a, 57a and 76a, raising the electrode 14a and lowering the counter-weight 83a, so that the parts may 55 assume the positions indicated in dot-dash lines in Fig. 3. By rotating the shaft in a clockwise direction the electrode 14a is lowered and the counter-weight 83a is raised.

60 Thus a simple and economically constructed apparatus for raising and lowering the electrodes with a minimum of power is provided, requiring a minimum number of sheaves directly over the intense heat of the furnace and including no bearings or supporting framework directly over the central portion of the

furnace. Moreover, the improved apparatus herein described presents a relatively small obstructing surface acting to restrict the direct upward flow of the hot gases from the furnace, thereby decreasing the deleterious effect of the same upon the electrode suspending apparatus and supporting framework therefor, located above the furnace.

70 It has been found in actual practice that the improved electrode suspending apparatus is advantageous over types previously employed, in requiring less expenditure in fabrication, installation and maintenance; and in promoting adjustability of the electrodes for 75 efficient and satisfactory furnace operation. 80

I claim:

1. In an electric furnace having a vertically disposed electrode suspended therein, a transformer located at the rear of the furnace, and current conductors extending between the transformer and the electrode, means for vertically adjustably suspending the electrode, said means including a horizontal rotatable shaft located in substantially parallel relation to said conductors, means for rotating the shaft, and flexible means operatively connecting the shaft with the electrode for moving the electrode vertically when the shaft is rotated.

85 2. In an electric furnace having a vertically disposed electrode suspended therein, a transformer located at the rear of the furnace, and current conductors extending between the transformer and the electrode, means for vertically adjustably suspending the electrode, said means including a horizontal rotatable shaft located in substantially parallel relation to said conductors, means for rotating the shaft, flexible means 90 operatively connecting the shaft with the electrode for moving the electrode vertically when the shaft is rotated, a counter-weight, and flexible means operatively connecting the shaft with the counter-weight.

95 3. In an electric furnace having a vertically disposed electrode suspended therein, a transformer located at the rear of the furnace, and a series of current conductors extending between the transformer and the electrode, means for vertically adjustably suspending the electrode and conductors immediately adjacent thereto, said means including an electrode holder for clamping around the electrode, a conductor holder, conductors connected between the electrode holder and the conductor holder, a horizontal rotatable shaft located in substantially parallel relation to the series of current conductors, means for rotating the shaft, flexible means operatively connecting the electrode holder with the shaft, and flexible means operatively connecting the conductor holder with the shaft.

100 4. In an electric furnace having a vertically disposed electrode suspended therein, a transformer located at the rear of the furnace, and

a series of current conductors extending between the transformer and the electrode, means for vertically adjustably suspending the electrode and conductors immediately adjacent thereto, said means including an electrode holder for clamping around the electrode, a conductor holder, conductors connected between the electrode holder and the conductor holder, a horizontal rotatable shaft

- 5 located in substantially parallel relation to the series of current conductors, means for rotating the shaft, a pair of sheaves keyed on the shaft and adjustable longitudinally thereof, a flexible member secured at one end to one 10 of the sheaves, and at its other end to the holder, and another flexible member secured at one end to the other sheave and at its other end to the conductor holder.

5. Electrode suspending means for a furnace having vertically disposed electrodes therewithin and current conductors leading from the rear of the furnace to the electrodes in substantially parallel relation to the longitudinal axis of the furnace, the suspending 20 means including a horizontal rotatable shaft for each electrode located in parallel relation to said longitudinal axis, means for driving the shaft, flexible means operatively connected between the shaft and the electrode for 25 moving the electrode vertically, and a framework for supporting the shaft and the shaft driving means above the furnace, said framework being located at the rear of the furnace and terminating substantially over the rear 30 wall thereof.

6. In a furnace having a vertically disposed electrode in the central portion thereof and current conductors leading from the rear of the furnace to the electrode in substantially parallel relation to the longitudinal axis of the furnace, a supporting framework located above the conductors, the framework including a laterally extending cross member located substantially above the rear portion 40 of the furnace, a horizontal shaft located in parallel relation to the longitudinal axis of the furnace and journaled in a bearing supported on said cross member, the forward end of the shaft extending beyond the cross member and over the electrode, and means operatively connecting the forward end of the shaft and the electrode.

7. In combination with a furnace having a vertically disposed electrode therewithin, means for vertically adjustably suspending the electrode including, a sheave rotatably mounted above the electrode, means for rotating the sheave, a separable electrode holder including two halves for clamping around the electrode, and flexible hanger means connected between the sheave and the holder adapted to move the holder halves away from the electrode when the holder is unclamped.

8. In combination with a furnace having a vertically disposed electrode therewithin,

means for vertically adjustably suspending the electrode including a sheave rotatably mounted above the electrode, means for rotating the sheave, an electrode holder adapted for clamping around the electrode and having inner arcuately curved surfaces, means operatively connecting the holder to the sheave, contact pads interposed between the holder and opposite sides of the electrode and having outer arcuately curved surfaces contacting with and conforming to the inner arcuately curved surfaces of the electrode holder, whereby the electrode may be twisted axially without disturbing the position of the holder.

9. In combination with a furnace having a vertically disposed electrode therein and current conductors leading to the electrode, means for vertically adjustably suspending the electrode and conductors, said means including a separable electrode holder including two halves for clamping around the electrode, a separable conductor holder including two halves, the current conductors being connected between the electrode holder and conductor holder, a sheave rotatably mounted above the electrode holder, means for rotating the sheave, a second sheave rotatably mounted above the conductor holder, means for rotating the second sheave, flexible hanger means connecting each of the conductor holder halves to the second sheave, and flexible hanger means connecting each of the electrode holder halves to the first sheave and adapted to swing each of the electrode holder halves and conductor holder halves and conductors connected therebetween as a unit outwardly away from the electrode when the two halves of the electrode holder are unclamped.

10. Electrode suspending means for a furnace having a vertically disposed electrode therein including a framework located above the furnace and spaced horizontally from the electrode, a substantially horizontal rotatable shaft supported on and extending beyond the framework, the end of the shaft being located substantially directly over the electrode, and means operatively connecting the end of the shaft and the electrode.

11. Electrode suspending means for a furnace having a vertically disposed electrode therein including a framework located above the furnace and spaced horizontally from the electrode, a substantially horizontal rotatable shaft supported on and extending beyond the framework, the end of the shaft being located substantially directly over the electrode, a sheave fixed upon the end of the shaft, and flexible means operatively connecting the sheave with the electrode.

12. In a furnace having a vertically disposed electrode in the central portion thereof, an overhead framework including a horizontal cross member located substantially above a wall of the furnace, a substantially horizontal shaft journaled in a bearing supported on

the cross member, the forward end of the shaft extending beyond the cross member and over the electrode, and means operatively connecting the forward end of the shaft and the electrode.

In testimony that I claim the above, I have hereunto subscribed my name.

ALEXANDER G. RIPBERGER.
